WILLIAM VELLETTE MILLER, OF BAYONNE, AND GEORGE PERCIVAL RICE,
OF RUTHERFORD, NEW JERSEY, ASSIGNORS, BY MESNE ASSIGNMENTS,
TO THE EXCELLOGRAPH CO.

PHOTOGRAPHIC PROJECTING-MACHINE.

SPECIFICATION forming part of Letters Patent No. 623,410, dated April 18, 1899.

Application filed February 12, 1898. Serial No. 670,134. (No model.)

To all whom it may concern:

Be it known that we, WILLIAM VELLETTE MILLER, of Bayonne, in the county of Hudson, and GEORGE PERCIVAL RICE, of Rutherford, in the county of Bergen, State of New Jersey, have invented a new and Improved Photographic Projecting-Machine, of which the following is a full, clear, and exact description.

The invention relates to vitascopes, kinematographs, kinetoscopes, biographs, and similar machines; and its object is to provide a new and improved photographic projecting-machine arranged to impart a positive intermittent traveling motion to a film without danger of vibration of the film while at rest, so as to insure the production of a perfect picture, the film being positively fed equal distances without the slightest variation to insure a complete and full registration of every picture with the field of the lens.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a plan view of the improvement. Fig. 2 is a sectional front elevation of the same on the line 2 2 of Fig. 1. Fig. 3 is an enlarged transverse section of part of the improvement on the line 3 3 of Fig. 4. Fig. 4 is an enlarged sectional front elevation of the same on the line 4 4 of Fig. 3. Fig. 5 is a transverse section of the same on the line 5 5 of Fig. 4. Fig. 6 is a similar enlarged view of another part of the improvement on the line 6 6 of Fig. 1, and Fig. 7 is a longitudinal section of the oscillating and sliding shaft and adjacent parts.

The film A, made in the form of a continuous sheet, is provided on its sides with the usual equidistant apertures A', adapted to be engaged by the feed mechanism, as herein-after more fully described, for imparting an intermittent traveling motion to the film through a slide B, having an opening B' in

the field of the lens for permitting the projecting of a picture on a screen or for making exposures in the usual manner. The slide B is preferably disposed vertically for the film to travel in a similar direction through the slide, and the latter is attached to a tube B², fitted to slide in a casing B³, secured to the bracket C' of the main frame C, on which the machine is mounted. A rack-and-pinion movement B⁴ B⁵ serves to impart a sliding motion to the tube B² in its tubular casing B³ for conveniently introducing the film into the slide at the time the slide is out of range with the feed mechanism for the film.

The feed mechanism consists principally of two wheels D D', placed a suitable distance apart and formed with peripheral sprockets D², adapted to engage the apertures A' in the sides of the film A at opposite sides of the slide-opening B', the said wheels D D' rotating intermittently in unison, so as to impart an intermittent traveling motion to the film and bring successive spaces of the film into the opening B', and consequently into the field of the lens or other device. The feed-wheels D D' leave a clear space between their opposite faces for the uninterrupted passage of the light to and through the slide-opening B', the wheel D being secured to a shaft E, turning at one end in a bearing C⁵, the main body of said shaft being mounted to turn in a hollow shaft F, while the other wheel D' is secured on a shaft E', mounted to turn in a bearing C², carried by the frame C. The two shafts E E' are in alinement with each other, but extend in opposite directions from their wheels, so as to leave a clear space between the opposite faces of the wheels for the purpose mentioned.

The hollow shaft F is mounted to turn and to slide longitudinally in suitable bearings C³ C⁴, carried by the frame C, and on the end of said hollow shaft, adjacent to the wheel D, is secured an L-shaped arm G, having its horizontal member G' overhanging the peripheral surfaces of the wheels D D'. On the under side of said member G' are formed or secured radially-extending teeth G² G³, adapted to engage registering notches D³ D⁴, respectively,

formed in the peripheral surfaces of the wheels D D', respectively, as will be readily understood by reference to Figs. 3 and 4.

As shown in Fig. 3, the wheels D D' are provided with eight such registering notches D³ D⁴; but it is evident that a larger or smaller number of notches may be employed, according to the length of the pictures on the film, it being understood that the arm G engages with its teeth G² G³ a pair of registering notches and then swings and turns the wheels one-eighth of a revolution at a time to feed the film in the slide B a corresponding distance—that is, the height of a picture—so as to bring successive pictures into the opening B'.

In order to impart a rocking motion to the hollow shaft F and the arm G carried thereby, said hollow shaft is provided with a downwardly-extending arm H, carrying a friction-roller H', in engagement with a cam-groove I', formed in the periphery of the cam I, secured to a cam-shaft J, journaled in suitable bearings C⁶, held on the frame C. The groove I' in the cam I is so arranged that for every full revolution of the said cam a full forward-and-backward stroke is given to the arm G. The cam-shaft J is provided with a gear-wheel J', in mesh with a gear-wheel K', held on a shaft K, journaled in bearings C⁷ on the frame C, and the outer end of said shaft is provided with a grooved pulley K² or other means connected with other machinery for imparting a continuous rotary motion to said shaft K, the motion of which is transmitted by the gear-wheels K' J' to the cam-shaft J. A sliding motion is given to the hollow shaft F from the cam-shaft J at the time the arm H is at a standstill and the friction-roller H' thereof travels through the straight portion of the cam-groove I'. For this purpose the hollow shaft F is provided with a collar L, formed in its periphery with an elongated groove L', engaged by a friction-roller N', carried on the upwardly-extending member of a three-armed lever N, having its horizontal member formed with a fork N², straddling a four-faced cam P, secured on the cam-shaft J. The three-armed lever N is fulcrumed loosely on a shutter-shaft O, carrying the usual shutter O', having its opening O³ in alignment with the opening B' during the period of rest of the film A, said shaft O and its shutter O' being driven from the cam-shaft J in unison with the feed mechanism for the film. The shaft O is for this purpose provided with a gear-wheel O², in mesh with an intermediate gear-wheel O³, in mesh with a gear-wheel O⁴, secured on the cam-shaft J.

The downwardly-extending member of the three-armed lever N is connected by a link Q with a bolt R, forming a locking device for the wheels D D' during the period of rest, said bolt having a downwardly-extending arm R', pivoted at R² to the frame C of the machine. The bolt R is provided at its ends with teeth R³ R⁴, adapted to engage a pair of registering notches D³ D⁴ in the wheels D D'

at the time the said notches are in a lower-most position.

By reference to Fig. 2 it will be seen that the three-armed lever receives a swinging motion from the cam P on the cam-shaft J, so that a sliding motion is given to the hollow shaft F and its arm G in one direction, while the link Q imparts a rocking motion in the opposite direction to the bolt R. Thus by this arrangement the bolt R and the arm G simultaneously receive motion for moving the teeth G² G³ of the arm G in mesh with a pair of notches D³ D⁴ at the top of the wheels D D' at the time the teeth R³ R⁴ move out of engagement with a corresponding pair of registering notches at the bottoms of the wheels D D', and a reverse movement takes place when the arm H swings in an opposite direction, so that the teeth G² G³ move out of mesh with their notches at the time the teeth R³ R⁴ move in mesh with the notches at the bottoms of the wheels. As this movement of the teeth of the arm G and that of the locking-bolt R takes place at the same time, it is evident that the wheels D D' are positively locked against rotation during the period of rest, principally, however, by the bolt R, assisted by the arm G, prior to the beginning of the oscillating movement of the arm and at the end of the said movement.

It is understood that when the machine is in motion the cam I by its connection with the hollow shaft F imparts a rocking motion to the latter and to the arm G, and the other cam P by its connection with said hollow shaft F causes the same to slide in a longitudinal direction in such a manner that the oscillating and sliding movements alternate. Thus when the several parts are in the position shown in Figs. 1 and 2 the wheels D D' are at a standstill near the end of the period of rest, and when the shaft J rotates in the direction of the arrow a' (see Fig. 2) then the cam P acts on the three-armed lever N and shifts the shaft F and the arm G in the direction of the arrow b' to move the teeth G² G³ out of engagement with the notches D³ D⁴ at the top of the wheels D D', (see Fig. 4,) and at the same time shifts the bolt R from right to left in the inverse direction of the arrow b' to move the teeth R³ R⁴ in engagement with the pair of registering notches D³ or D⁴ at the bottom of the wheels D D'. This takes place during one-fourth of a revolution of the shaft J, and during which time the friction-roller H' travels in a straight portion of the cam-groove I', so that the hollow shaft F is not rocked in its bearing. During the next one-fourth revolution the lever N remains at a standstill, while the cam I imparts a swinging motion to the arm H to swing the arm G in the direction of the arrow c (see Fig. 3) to bring the teeth G² G³ in alignment with the next pair of registering notches D³ D⁴. During the next one-quarter revolution the friction-roller H' travels in the straight part of the cam-groove I', so that the rocking of the

shaft F ceases; but during this quarter-revolution the cam P again acts on the lever H and swings the same in an opposite direction to shift the hollow shaft F in the inverse direction of the arrow b', so as to move the teeth G² G³ in mesh or engagement with the registering notches, as indicated in dotted lines in Fig. 3. At the same time the bolt R is shifted from the left to the right to move its teeth out of engagement with the notches D³ D⁴ at the bottom of the wheels D D'. During the next quarter-revolution of the shaft J a swinging motion in the inverse direction of the arrow c' is given by the cam I' to the shaft F and its arm G, so that the wheels D D' are now given one-eighth of a turn to feed the film A downward in the slide B and bring the next picture into register with the slide-opening B'. The above-described operation is then repeated—that is, upon a further turning of the shaft J the bolt R is moved into position for locking the wheels D D', while the arm G moves with its teeth out of mesh with said wheels, then swings to the position shown in dotted lines in Fig. 3, then moves in mesh with the wheels, while the bolt moves out of mesh with the same, and then the arm is rocked back to its former position to again turn the wheels D D' for again feeding the film, as described.

Now it is evident that by the improvement specified a positive feeding of the film takes place without danger of vibration of the film while at rest, as the feed mechanism is positively locked in position during the period of rest by the locking-bolt R and partly by the teeth of the arm G, as previously mentioned. Furthermore, the film is positively fed equal distances without the slightest vibration, thereby insuring a full registration of every picture with the lens.

The mechanism described permits of running the machine at a very high rate of speed with absolute registration of the pictures with the field of exposure.

It is especially noted that the feed mechanism engages the film at the sides of the slide-opening, so that the film is not loose at the said opening, but is locked at this very point by the feed mechanism during the period of rest and is bodily moved at this point by the same means during the period of feeding. As the feed mechanism is rigidly locked with the film, the latter cannot possibly vibrate and mar the effect.

Having thus fully described our invention, we claim as new and desire to secure by Letters Patent—

1. A photographic projecting-machine, provided with spaced feed-wheels for engaging the film at opposite sides of the slide or exposure opening, said wheels having an unobstructed passage for the light between them, and a positive mechanism acting directly on the said wheels for imparting an intermittent rotary motion to the same, substantially as described.

2. A photographic projecting-machine, provided with spaced feed-wheels for engaging the film at opposite sides of the slide or exposure opening, said wheels having an unobstructed passage for the light between them, a positive mechanism acting directly on the said wheels for imparting an intermittent rotary motion to the same, and a locking device operating in conjunction with the said operating mechanism and adapted to engage the said wheels during the period of rest to positively lock the wheels against rotation, substantially as described. 70

3. A photographic projecting-machine, provided with spaced feed-wheels for engaging the film at opposite sides of the slide or exposure opening, said wheels having an unobstructed passage for the light between them, and a positive mechanism acting directly on the said wheels for imparting an intermittent rotary motion to the same, the said mechanism holding said wheels temporarily in a locked position both prior to the beginning of the movement and at the end thereof, substantially as described. 85

4. A photographic projecting-machine, provided with independently - mounted feed-wheels, for engaging the film at opposite sides of the slide or exposure openings and an arm having an oscillating and sliding movement, and adapted to engage said feed-wheels to impart an intermittent rotary motion to the same, substantially as shown and described. 95

5. A photographic projecting-machine, provided with independently - mounted feed-wheels, for engaging the film at opposite sides of the slide or exposure opening and an arm having alternate oscillating and sliding movements, and adapted to engage said feed-wheels to impart an intermittent rotary motion to the same, substantially as shown and described. 105

6. A photographic projecting-machine, provided with independently - mounted feed-wheels for engaging the film at opposite sides of the slide or exposure opening having peripheral registering notches placed equal distances apart, and an arm having alternate oscillating and sliding movements, the arm overhanging the peripheries of the wheels and having teeth adapted to engage and disengage said notches to impart an intermittent rotary motion to the wheels, substantially as shown and described. 115

7. A photographic projecting-machine, provided with independently - mounted and notched feed-wheels for engaging the film at opposite sides of the slide or exposure opening, an arm having alternate oscillating and sliding movements, and formed with teeth for alternately engaging and disengaging the notches, to intermittently turn the wheels, and a locking-bar operating in unison with the said arm, to engage and disengage the said notches but in a reverse order to the arm, substantially as shown and described. 125

8. A photographic projecting-machine, provided with independently - mounted and

- notched feed-wheels for engaging the film at opposite sides of the slide or exposure opening, an arm having alternate oscillating and sliding movements, and formed with teeth for alternately engaging and disengaging the notches, to intermittently turn the wheels, and a locking-bar operating in unison with the said arm, to engage and disengage the notches but in a reverse order to the arm, the arm and bar being simultaneously in engagement with the notches during part of the sliding motion of the arm and the movement of the bar, substantially as shown and described.
9. A photographic projecting-machine, comprising a revoluble cam-shaft, a rocking and sliding shaft, an arm carried by the said rocking and sliding shaft, a film-feed mechanism receiving an intermittent rotary motion from the said arm, and intermediate mechanism between the said cam-shaft and the rocking and sliding shaft, to impart alternate oscillating and sliding motions to the said rocking and sliding shaft and the arm carried thereby, substantially as shown and described.
10. A photographic projecting-machine, comprising a feed mechanism, an oscillating and slidable arm for imparting an intermittent motion to the said feed mechanism, a driven cam-shaft having a plurality of cams, a shaft mounted to turn and to slide, and carrying said arm, a connection between one of the cams and the last-mentioned shaft, to impart a rocking motion to the same, and a lever for connecting the second cam with said last-mentioned shaft, to impart a sliding motion thereto, substantially as shown and described.
11. A photographic projecting-machine, comprising a feed mechanism, an oscillating and slidable arm for imparting an intermittent motion to the said feed mechanism, a driven cam-shaft having a plurality of cams, a shaft mounted to turn and to slide, and carrying said arm, a connection between one of the cams and the last-mentioned shaft, to impart a rocking motion to the same, a lever for connecting the second cam with said last-mentioned shaft, to impart a sliding motion thereto, and a locking-bar connected with the said lever, and adapted to engage the feed mechanism and lock the same in place during the period of rest, substantially as shown and described.
12. A photographic projecting-machine, provided with a feed mechanism, comprising two spaced and intermittently rotating wheels mounted on independent shafts and engaging the film on opposite sides of the slide or exposure opening, substantially as described.
13. A photographic projecting-machine, provided with a slide for the film, and a feed mechanism having an intermittent rotary motion, and comprising two spaced wheels mounted on alined and oppositely-extending shafts and rotating intermittently in unison for engaging the film in the slide at opposite sides of the slide-opening, whereby a clear space for the uninterrupted passage of light to and from the slide-opening, will be left between the opposing faces of the wheels substantially as shown and described.
14. In a photographic projecting-machine, the combination of two spaced feed-wheels for engaging the sides of the film at opposite sides of the slide-opening, said wheels being provided with peripheral registering notches, an arm provided with teeth for simultaneously engaging the notches of the said wheels, and means for imparting an alternate sliding and oscillating movement to said arm, substantially as described.
15. In a photographic projecting-machine, the combination of two spaced feed-wheels mounted on independent and alined shafts and adapted to engage the sides of the film at opposite sides of the slide-opening, said wheels being provided with peripheral and registering notches, an arm provided with teeth for engaging the said wheels, and means for imparting an alternate sliding and oscillating movement to said arm, substantially as described.
16. In a photographic projecting-machine, the combination with two spaced feed-wheels mounted on independent and alined shafts, said wheels being provided with peripheral and registering notches, an arm mounted to slide and oscillate and provided with teeth for engaging the notches of the said wheels, means for oscillating the arm, means for sliding said arm, a locking-bolt adapted to engage the notches of the feed-wheels, and means for operating the said bolt from the means that slide the said arm, substantially as described.
17. In a photographic projecting-machine, the combination with feed-wheels having peripheral and registering notches, and mounted on independent and alined shafts, of a hollow shaft mounted to slide and turn upon the shaft of one of the feed-wheels, an angular arm secured to the hollow shaft, adjacent the feed-wheel carried thereby and provided with teeth on its horizontal member for engaging the notches of the feed-wheels, and means for sliding and turning the said hollow shaft, substantially as described.
18. In a photographic projecting-machine, the combination with feed-wheels having peripheral and registering notches and mounted on independent and alined shafts, of a hollow shaft mounted to slide and turn upon the shaft of one of the feed-wheels, an angular arm secured to the hollow shaft adjacent to the feed-wheel carried thereby and provided with teeth on its horizontal member for engaging the notches of said wheels, means for rocking the hollow shaft, means for sliding said hollow shaft, a locking-bolt provided with teeth adapted to engage the notches of the feed-wheel, and means for operating the locking-bolt from the shaft-sliding means, substantially as described.
19. In a photographic projecting-machine, the combination with feed-wheels provided

with peripheral and registering notches and mounted on independent and alined shafts, of a hollow shaft mounted to slide and turn upon the shaft of one of the feed-wheels, an 5 angular arm secured to the hollow shaft and provided with teeth on its horizontal member for engaging the notches of the feed-wheels, a shaft provided with a plurality of cams, an arm on the end of the hollow shaft opposite that carrying the toothed arm, said arm being engaged by one of the cams of said shaft, and a pivoted lever having one member engaging a cam on the said shaft and another member loosely connected with the said hollow shaft, 10 substantially as described.

20. In a photographic projecting-machine, the combination with feed-wheels having peripheral and registering notches and mounted on independent and alined shafts, of a hollow 20 shaft mounted to slide and turn on the shaft of one of the feed-wheels, an angular arm secured to the hollow shaft and provided with teeth engaging the notches of the said wheels, a shaft provided with two cams, an arm on the end of the hollow shaft opposite that carrying the angular and toothed arm, said arm engaging one of the cams of the shaft, a pivoted three-armed lever having one arm en-

gaging the other cam of the said shaft and another arm loosely engaging a collar on the 30 hollow shaft, a pivoted locking-bar provided with teeth for engaging the notches of the feed-wheels, and a link connecting the third arm of the said lever with the locking-bar, substantially as described.

35

21. In a photographic projecting-machine, the combination with a cam-shaft, and a shutter-shaft, of feed-wheels mounted on independent and alined shafts, means for imparting intermittent rotary motion to the feed-wheels from the cam-shaft, and gearing between the cam-shaft and the shutter-shaft for operating the latter from the former, substantially as described.

40

22. In a photographic projecting-machine, 45 the combination with a feed mechanism, of a tubular casing, a tube fitted to slide in the casing, a slide having an opening in it and secured to said tube, and means for sliding said tube in its casing, substantially as and 50 for the purpose set forth.
